HERBERT M. KNIGHT, OF UPPER MONTCLAIR, NEW JERSEY

SHEET PILING

Application filed September 2, 1930. Serial No. 479,277.

This invention relates to sheet-piling, and more specially to sheet-pile cores introduced in levees to prevent seepage through such levee, and at the same time provide a flexible means of increasing the height of such a pile core above the top thereof as will prevent over-topping of said levee by floods of super-stage extent.

One of the objects of the invention is to provide a cap upon the top of a pile core, said cap having imbedded therein a means for holding a temporary stop-plank mechanism in position. Another object of the invention is to provide a cap upon the upper extremities of such an interior pipe-core, said cap overcoming the inequalities in the height liable to occur in driving such sheet-piling. A further object of the invention is to provide a means for temporarily holding in position a forming means used in connection with the pouring of such a cap. Another object of the invention is to provide a means of preventing seepage of water between such a cap and the super-imposed stop-planks. Still another object of the invention is to provide a holding means whereby said stop-planks are prevented from floating when rendered buoyant by rising water. Still other objects of the invention will appear from the accompanying plans and specifications.

While the accompanying plans and specification illustrate and describe the preferred embodiment of the invention, they are illustrative only and are not to be considered as indicating the only form and application of the invention nor as excluding other forms and applications in which the invention can be used.

The drawings accompanying this application are 13 in number and are as follows:

Fig. 1 is a longitudinal section on the line 1—1 of Fig. 2; Fig. 2 is a cross-section on the line 2—2 of Fig. 1; Fig. 3 is a longitudinal section on the line 3—3 of Fig. 2; Fig. 4 is a longitudinal section on the line 4—4 of Fig. 2; Fig. 5 is a front elevation of a capping and stop-plank attachment to a sheet pile core; Fig. 6 is a cross-section of a pile core with its capping and stop-plank attachment; Fig. 7 is a front elevation of the hollow attachment box on the line 7—7 of Fig. 9; Fig. 8 is a vertical section of such an attachment box on the line 8—8 of Fig. 9; Fig. 9 is a horizontal section of such a box on the line 9—9 of Fig. 7; Fig. 10 is a vertical section of such a box on the line 10—10 of Fig. 9; Fig. 11 is a horizontal section of a pile core on the line 11—11 of Fig. 12; Fig. 12 is a transverse section of a pile core on the line 12—12 of Fig. 11, and Fig. 13 is a face elevation of such a core.

7 is a front elevation of the hollow attachment box on the line 7—7 of Fig. 9; Fig. 8 is a vertical section of such an attachment box on the line 8—8 of Fig. 9; Fig. 9 is a horizontal section of such a box on the line 9—9 of Fig. 7; Fig. 10 is a vertical section of such a box on the line 10—10 of Fig. 9; Fig. 11 is a horizontal section of a pile core on the line 11—11 of Fig. 12; Fig. 12 is a transverse section of a pile core on the line 12—12 of Fig. 11, and Fig. 13 is a face elevation of such a core.

Referring to the drawings in which similar figures refer to similar parts:—1 is a levee, in which has been driven a pre-cast pile core 2, having depressions 3 in the faces thereof. A mass concrete monolithic cap 4 is poured upon and around the heads of the piles so driven. Tie-rods 5, connecting said pre-cast piles and said cap, are inserted in the heads 6 of said piles. Open end boxes 7, staggered alternately on opposite sides of said cap are introduced in advance of the pouring of said cap and become integral parts of said cap after pouring. Uprights 8, are removably connected to said boxes by means of bolts 9, having heads 10, which said heads are capable of insertion within the hollow interior 11, of said box, but which cannot pass through the face slot 12. Nuts 13, with washers 14, engage the outer face of said uprights and removably attach said uprights to said boxes and said cap, the interior head of said bolt being brought into contact with the interior face 15, of said hollow interior of said box. Lugs 16, with holes 17, therein serve to locate such boxes in position during the pouring of said cap. A shelf 18, supports said box on said pre-cast pile and a fin 19, enters a depression 20, in said pile, thereby locating said boxes longitudinally of said pile. A depression 21, is formed in the top of said cap. Holes 22, are cast in said pile for tie-irons. Other holes 23, are cast in said piles for the insertion of a dog 24, adapted to support a sill 25, which acts as a supporting medium for face forms for use in pouring said cap.

Longitudinally oppositely offset extensions 26, and 27, are formed in said pre-cast piles, said extensions on opposite edges of

adjoining piles, overlapping. Re-entrant grooves 27, are juxtaposed in said overlapping extensions and keys 28, are inserted in said grooves attaching said adjacent piles together both laterally and longitudinally.

5 Bevelled corners 29, are provided on the corners of the piles.

Spreaders 30, separate said uprights from face-plates 31, bolts 32, attaching said uprights, spreaders and face-plates together. Stop-planks 33, are inserted in the space between said face-plates, the bottom of said stop-planks being housed in said depression of said cap. Grooves and bevels 34, serve to prevent a straight through joint between adjacent stop-planks. Fastening means 35, prevent the dislodgment of said stop-planks. Wash-pipe grooves 36, are provided at the heads of said piles.

For the protection of areas subject to periodic floods, levees are constructed of earth. As a means of strengthening said earthen levees a core-wall is introduced, which acts both as a means of added strength and also as an impervious layer, preventing infiltration with consequent softening of the levee material and subsequent erosion and washing away. Oftentimes however floods of greater or unprecedented height rise to or above the top of such an earthen levee and it thereafter becomes useless as a flood prevention means. As a temporary and emergency expedient the height of such levees is raised by means of sand bags or other quickly applied remedies, but such efforts are quite often ineffective as a complete protection against overtopping of a levee structure by an extreme flood.

This invention provides an entirely satisfactory means for preventing the overtopping of a levee, whether the flood stage be usual or extreme, with the advantage that after the passing of the flood stage the extraordinary means employed may be removed, and stored against a further demand for its replacement. At the same time the invention provides a perfectly impervious and indestructible centre core, preventing the seepage of water through the levee, and likewise the boring of rodents or similar animals therethrough, which latter results in holes being made in the levee through which the water enters and rapidly disintegrates the structure.

The essential feature of this invention consists in a means of rapidly attaching to and detaching from the central impervious core a stop-plank structure which can be progressively added to the top of the levee as increasing height of flood, and the subsequent receding thereof, make desirable or necessary. The method of attachment and detachment of such stop-plank structure is exceedingly simple and requires neither great skill nor machinery. The poured concrete cap in which

are imbedded the attachment boxes, overcomes slight variations in the elevation of the tops of the pre-cast pile core and offers a very satisfactory base for the stop-plank structure.

In the operation of installing such a structure, a sheet-pile core, preferably of pre-cast concrete, but not exclusively confined to such material, is driven in, or near the centre of the embankment, and to such a depth as to penetrate the natural soil underlying the same. This sheet-pile core may, or may not have recessed faces, such latter feature being employed to reduce the weight of the pile and at the same time decrease the skin friction during driving. These sheet-piles are preferably, though not necessarily, of the lapped variety, and are connected together with keys, such connection aiding in preserving the alignment of the piles while they are being driven, while they strengthen and hold the pile structure in position after driving, and at the same time make the core impervious and remove the objection to a pile structure with a straight joint therethrough. The piles are driven in advance of the pouring of the cap. In the driving of such piles a wash-pipe is usually employed, such wash-pipe being introduced into the key-way through a wash-pipe groove at the top of the pile and below the head thereof, such provision permitting of the economical and rapid insertion and removal of such wash-pipe, and at the same time preventing interference of said wash-pipe with the pipe driving hammer.

The piles are driven to substantially even depths so that their heads will be at approximately an even top elevation. After the driving of the pile core, a mass concrete cap is poured around and upon the tops of said piles, binding them together and offering an even bed for the superimposed stop-planks. The following means are provided to make the placing of this cap rapid and economical. A dog-hole is cast in the face of the pile, said dog-hole being preferably square. Into this dog-hole is driven a steel dog, usually with a square shank and adapted to engage and bind with the edges and interior surfaces of said hole. Upon the dogs is laid a sill adapted to rest upon the dogs, and at the same time that it becomes the bottom form for the superimposed cap it is designed to engage the side forms required to retain the said cap while it is in a plastic state.

The said cap is provided with a depression, in the top thereof adapted to receive and anchor the bottom member of the stop-plank assemblage. This depression not only anchors the stop-planks to the cap, but in addition seals the point of connection of the cap and the lowest stop-plank member, thereby creating a water tight joint, preventing seepage, or passage of water therethrough.

For the purpose of more intimately uniting the sheet-pile core and the superimposed

cap, holes are cast through said sheet-piles, into which re-inforcing bars are inserted. The lower ends of these bars are bent normal to the length of these re-inforcing bars, and serve to engage the concrete of the cap so as to unite the pile and the cap together.

An open ended metal box is cast into and with the superimposed cap, said box having a slot on the outer or exposed face thereof extending throughout the height of the said box. The slot is wide enough to permit the shank of a bolt to enter and slide therein, but it is so narrow as to prevent the passage of the head attached to said shank. The interior area of the box is slightly larger than the size of the bolt-head. Except for the open upper end and the face slot the box is entirely enclosed. Perforated lugs in the face thereof serve to temporarily hold the box in position during the pouring of the concrete, while back lugs engage with the mass concrete and prevent the displacement of the box after the pouring of the cap. To position the box accurately a shelf is cast upon the back which rests upon the top of the pre-cast sheet-pile core, and a fin projects from the back of the box which fits into a slot cast into the head of the sheet-pile. By means of this fin and slot the boxes are automatically and accurately located on opposite sides of the sheet-pile core, and the shelf resting upon the heads of the piles serves immediately to locate the boxes in a vertical position.

Uprights are provided which are connected to face-plates against which the stop-planks directly rest. On account of the width of the cap, and in order to secure as light weight as is consistent with strength in the members to be assembled at the time of flood, spreaders are employed to separate the uprights and face-plates at their proper distance apart, so that stop-planks can be snugly inserted between the inner faces of opposite and staggered face-plates. Uprights, spreaders and face-plates are rigidly connected together by bolts passing through all three members, the heads of said bolts being housed in the face-plates, and having nuts and washers on the outer face of said uprights. The face-plates are usually of such length as that when they are in position on the levee their lower ends rest upon the upper surface of the superimposed cap. The uprights are longer than the face-plates, and their lower ends have bolts therein the heads of which are adapted to enter the hollow inner area of the box while the shank of said bolt passes through the slot in the outer face of said box. The nut on the outer end of said bolt is adapted to engage, through a washer, with the outer face of said upright, tightening said nut, after the head thereof has entered said box, serving to rigidly attach said upright with its connected spreader and face-

plate to said cap and sheet-pile core, they thereby becoming capable of sustaining the pressure due to the head of water created by the extreme flood stage, thereby preventing the overtopping of the levee and its sheet-pile core, and preventing inundation. Loosening the aforesaid outer nut permits the removal of the upright and its attached spreader and face-plate, when they can be removed and preserved against a future need.

The stop-planks which are inserted between the opposite and staggered face-plates have their edges grooved and beveled or otherwise similarly treated to prevent a straight through joint, which would permit easy infiltration of water. Means are provided to connect the stop-planks and face-plates, thereby overcoming the effect of buoyancy, and preventing the floating or moving upwardly of said stop-planks, due to the rising flood waters.

What I claim is:—

1. In a structure of the class described, the combination of pre-cast piles, a mass concrete cap engaging the tops of said piles and a stop-plank structure superimposed upon said cap and removably connected thereto.

2. In a structure of the class described, the combination of pre-cast piles, a mass concrete cap engaging the tops of said piles, a stop-plank structure superimposed upon said cap and removably connected thereto and said cap having a depression engaging said stop-plank structure.

3. In a levee system, a core-wall, a mass concrete cap on said core-wall and boxes in said cap.

4. In a levee system, a core-wall, a mass concrete cap on said core-wall and boxes in said cap, said boxes being positioned alternately on opposite sides of said cap.

5. In a levee system, a core-wall, a mass concrete cap on said core-wall and boxes in said cap, said boxes being open upwardly.

6. In a levee system, a core-wall, a mass concrete cap on said core-wall and boxes in said cap, said boxes having a slot in the outer faces thereof.

7. In a levee system, a core-wall, a mass concrete cap on said core-wall and boxes in said cap, said boxes having a shelf on the backs thereof for positioning the boxes with respect to the wall.

8. In a levee system, a core-wall, a mass concrete cap on said core-wall and boxes in said cap, said boxes having a fin on the back thereof for positioning the boxes with respect to the wall.

9. In a structure of the class described, the combination of pre-cast piles, a mass concrete cap engaging the tops of said piles, tie-rods engaging said piles and said caps, and a stop-plank structure superimposed upon said cap and removably connected thereto.

10. In a structure of the class described,

the combination of pre-cast piles, a mass concrete cap engaging the tops of said piles, boxes in said caps, uprights removably attached to said boxes, face-plates connected to said uprights, said uprights and said face-plates being positioned alternately on opposite sides of said cap and stop-planks superimposed upon said cap and abutting upon said face-plates.

11. In a structure of the class described, the combination of pre-cast piles, a mass concrete cap engaging the tops of said piles, boxes in said caps, uprights removably attached to said boxes, face-plates connected to said uprights, said uprights and said face-plates being positioned alternately on opposite sides of said cap, the upper surface of said cap having a depression and stop-planks registering in said depression and abutting upon said face-plates.

12. In a structure of the class described, the combination of pre-cast piles, a mass concrete cap engaging the tops of said piles, boxes in said caps, uprights removably attached to said boxes, face-plates connected to said uprights, said uprights and said face-plates being positioned alternately on opposite sides of said cap, the upper surface of said cap having a depression, stop-planks registering in said depression and abutting upon said face-plates and means preventing the flotation of said stop-planks.

13. In a levee system, a sheet-pile core, said piles as units, consisting of a central portion and offset oppositely disposed edge portions, said edge portions of adjacent piles overlapping in a direction longitudinal to said core, said overlapping edge portions having juxtaposed re-entrant grooves, keys in said re-entrant grooves and the heads of said piles having fin notches, thereby spaced at regular intervals in the head of the said core.

14. In a levee system, a sheet-pile core, said piles consisting of a central portion and offset oppositely disposed edge portions, said edge portions of adjacent piles overlapping in a direction longitudinal to said core, said overlapping edge portions having juxtaposed re-entrant grooves, keys in said re-entrant grooves and the heads of said piles having dog holes, thereby spaced at regular intervals in the head of said core.

15. In a structure of the class described, the combination of pre-cast piles, overlapping edge portions of said piles, juxtaposed re-entrant grooves in said overlapping edges, keys in said re-entrant grooves, a mass concrete cap engaging the tops of said piles, boxes in said cap, uprights removably attached to said boxes, face-plates connected to said uprights and stop-planks superimposed upon said cap and abutting upon said face-plates.

HERBERT M. KNIGHT.
